SPOOL

George H. Bird, Brooklyn, N. Y.

Application March 2, 1932. Serial No. 596,180

4 Claims. (Cl. 242—123)

This invention relates in general to spools and particularly to spools for ribbon and the like. Such spools usually include a hollow or tubular core of penetrable material such as cardboard, and end flanges on the extremities of the core for retaining the ribbon or the like on the spool. One object of my invention is to provide a spool of this character embodying novel and improved features of construction for connecting the end flanges to the core.

Another object is to provide means for connecting end flanges to a core in a spool of this character comprising a single piece or disc of sheet metal having lugs or prongs to extend into and penetrate the interior of the core, the prongs being forced into the core by deformation of the disc after the latter has been applied to the ends of the core.

Other objects are to provide such a spool which has substantially flat ends without any material projections, so that the spools may be conveniently arranged in stacked relation end to end, and to obtain other advantages and results as will be brought out by the following description.

Referring to the accompanying drawing in which corresponding and like parts are designated by the same reference characters throughout the several views,

Figure 1 is an end view of a spool embodying my invention.

Figure 2 is a vertical sectional view through the spool with portions of the end flanges broken away.

Figure 3 is a similar view showing the manner of applying the fastening disc.

Figure 4 is a transverse sectional view on the line 4—4 of Figure 2.

Figure 5 is a similar view on the line 5—5 of Figure 2.

Figure 6 is a longitudinal vertical sectional view through a modification of the invention wherein the fastening disc itself serves as an end flange, and showing the manner of inserting the fastening disc into the core, one fastening disc being omitted.

Figure 7 is a similar view showing the fastening disc secured to the core.

Figure 8 is an end view of a modification of the invention.

Figure 9 is a fragmentary vertical longitudinal sectional view through the construction shown in Figure 8 taken on the line 9—9 of Figure 8, and showing the manner of applying the fastening disc to the core.

Figure 10 is a similar view showing the fastening disc attached to the core.

Figure 11 is an end view of another form of spool embodying the invention.

Figure 12 is a fragmentary longitudinal vertical sectional view through one end thereof taken on the line 12—12 of Figure 11.

Figure 13 is a similar view showing the manner of attaching the fastening disc to the core.

Figure 14 is an end view of a further modification of the invention.

Figure 15 is a fragmentary vertical longitudinal sectional view on the line 15—15 of Figure 14, and

Figure 16 is a similar view showing the manner of attaching the fastening disc to the core.

Specifically describing the embodiment of the invention illustrated in Figures 1 to 5 inclusive, the spool comprises a tubular core 1 formed of suitable material such as cardboard, and the reference characters 2 designate end flanges for the core which have central openings 2a of a diameter somewhat less than the internal diameter of the core. These end flanges are secured to the ends of the core by fastening discs 3 each of which

comprises a single sheet of metal originally concavo-convex in cross section. Each disc has struck up therefrom a plurality of prongs 4 the bases of which are spaced from the center of the disc a distance somewhat less than the internal radius of the core 1. Each prong has an outwardly pointed end 5 and extends in the direction of the periphery of the disc 3, and the prongs project from the concave side of the disc, so that they may be easily slipped into the core from one end thereof.

In assembling the end flanges and fastening discs on the core, an end disc 2 is placed against one end of the core, after which a fastening disc 3 is placed against the outside of the end disc with the prongs 4 projecting into the core, as indicated in Figure 3 of the drawing. Then the central portion of the fastening disc is pressed inwardly of the core as shown in Figure 2 of the drawing. Due to the original concavo-convex shape of the fastening disc, when the central portion is so pressed inwardly of the core, the pointed ends 5 of the prongs are swung outwardly away

from the center of the disc and caused to penetrate the interior surface of the core, as clearly shown in Figure 2 of the drawing. The central portion of the disc thus becomes concavo-convex reversely to its original form and the prongs 4 project from the convex side of said central portion.

The fastening discs are thus firmly secured

to the core and clamp the end discs 2 between themselves and the core.

To prevent rotation of the end discs, each disc may be formed at the edges of its opening with notches 6 to receive the prongs 4, as shown in Figure 4. The prongs and fastening disc being non-rotatably secured to the core and interlocking with the discs through the prongs 4 and notches 6, effectually prevent rotation of the end flanges.

10 A modification of the invention is shown in Figures 6 and 7 wherein the fastening discs themselves serve as end flanges for the core. In this form of the invention, the fastening discs are made of a diameter greater than that of the core, and the end flanges 2 are omitted. The fastening discs are secured to the core in exactly the same manner as described in connection with Figures 1 to 5 inclusive.

20 A further modification of the invention is shown in Figures 8 to 10 inclusive where the fastening discs 7 serve as the end flanges for the core 8 and the fastening discs have stamped therefrom right-triangular ears 9 each having one arm radial of the disc and its base facing in the direction of the periphery of the disc. Each ear 9 also has a prong 10 projecting from its base. The fastening discs are originally concavo-convex in cross-section, and the ears 9 are so located 30 that the bases are spaced from the center of the disc a distance slightly less than the radius of the interior of the core so as to easily slip into the end of the core.

35 In attaching the fastening discs to the core, the ears are slipped into the core until the fastening disc abuts the end of the core whereupon the central portion of the disc is pressed inwardly of the core so as to cause the ears 9 to swing outwardly toward the inner surface of the core 40 which results in penetration of the core by the prongs 10 as shown in Figure 10 of the drawing. The fastening discs are thus firmly secured to the core by the prongs 10, and the ears 9 serve as supports for the core on the fastening discs, 45 the bases of the ears snugly fitting against the inner surface of the core.

Another spool embodying a modification of the invention is shown in Figures 11 to 13 inclusive. Here the fastening discs 12 are in general the same construction as the fastening discs 3 being concavo-convex in cross-section and having prongs 13 to engage the inside of the core 14. An annular shoulder 15 of a diameter substantially equal to the interior diameter of the core is formed on the concave side of each disc for supporting the core on the discs. These discs 12 are applied to the core in the same manner as are the discs 3, and the shoulder 15 provides a positive support for the core in addition to the prongs 13.

60 Figures 14 to 16 inclusive show another form of spool embodying a modification of the invention. In this form of spool the fastening discs 16 are originally flat and have prongs 17 struck-up therefrom at one side to originally slip easily into the core 18. After a disc has been placed against the end of the core as shown in Figure 16, a suitable tool is forced through the apertures 19 formed by the stamping of the prongs so as to force the prongs outwardly toward the periphery of the disc and into the inner surface of the core.

65 In all forms of the invention the fastening disc periphery has a central opening 20 to receive a 70 spindle upon which the spool may be mounted for

winding and unwinding material on or from the spool, and preferably an integral inturned annular flange is provided at the edge of the opening to reinforce the central portion of the disc.

80 It will be observed that in all forms of the invention, the ends of the spool are substantially flat, so that the spools may be firmly stacked in endwise relation. The fastening means comprises a single piece of metal and may be secured to the core of the spool by a simple operation. Accordingly, a spool embodying the invention can be made quickly and economically, and at the same time will be strong and durable.

85 It will be understood that the end flanges 2 may be used in any form of the invention, according to the purpose for which the spool is to be used.

90 While I have shown and described the invention as embodied in certain details of construction it should be understood that many modifications and changes may be made in the construction of the spool without departing from the spirit or scope of the invention.

95 Having thus described my invention, what I claim is:

100 1. A spool comprising a tubular core of penetrable material, end flanges therefor, and a fastening device securing each end flange to one end of said core, said fastening device comprising a metal disc overlying said end flange and having a concavo-convex central portion with a circular row of prongs projecting from the convex side thereof and penetrating the interior walls of said tube, said disc having initially been 105 reversely concavo-convex in cross-section with said prongs projecting from the concave side thereof and at a distance from the center of the disc less than the radius of the interior of said tube, and the central portion of said disc having been pressed inwardly of said core to 110 swing said prongs toward the periphery of the disc and cause the prongs to penetrate the interior walls of said core.

115 2. A fastening device for securing end flanges 120 on a tubular core of penetrable material, comprising a concavo-convex metal disc having a circular row of prongs projecting from the concave side thereof and spaced from the center of the disc a distance slightly less than the radius 125 of the interior of said tubular core, so that by placing said disc against the end of said core with said prongs extending into the core and pressing the central portion of said disc inwardly of said core, said prongs will be swung 130 toward the periphery of the disc and will penetrate the interior walls of said core.

135 3. The spool set forth in claim 1 wherein said end flanges have central openings somewhat smaller in diameter than the interior of said core, and the edges of said openings are formed with notches to receive said prongs to prevent rotation 140 of said end flanges on the core.

145 4. A fastening device for securing end flanges on a tubular core of penetrable material, comprising a concavo-convex metal disc having a plurality of right triangular ears stamped therefrom and projecting from the concave side thereof with one leg of each triangular ear substantially radial of said disc, the bases of said ears 150 being spaced from the center of the disc a distance substantially equal to the radius of the interior of said core and having prongs projecting therefrom.
